UNITED STATES PATENT OFFICE

93,934

DESIGN FOR A LIGHT PROJECTOR OR SIMILAR ARTICLE

Joseph Levy, New York, N. Y.

Application October 16, 1934, Serial No. 53,629

Term of patent 7 years

To all whom it may concern:

Be it known that JOSEPH LEVY, a citizen of the United States, and resident of New York city, in the county of Kings and State of New York, has invented a new, original, and ornamental Design for Light Projectors or Similar Articles, of which the following is a specification, reference being had to the accompanying drawing, forming

part thereof, in which the figure is a perspective view of a light projector embodying the new design.

I claim:

The ornamental design for a light projector or similar article, as shown.

Dated October 12, 1934.

JOSEPH LEVY.
